UNITED STATES PATENT OFFICE.

PHINEAS H. ADAMS, JR., AND ORSEMAS T. X. ADAMS, OF CHICAGO, ILLINOIS,
ASSIGNORS TO MELINDA PECK, OF SAME PLACE.

APPARATUS FOR DECOMPOSING METALLIC SALTS AND DESULPHURIZING ORES.

SPECIFICATION forming part of Letters Patent No. 416,815, dated December 3, 1889.

Application filed March 11, 1889. Serial No. 302,878. (No model.)

To all whom it may concern:

Be it known that we, PHINEAS H. ADAMS, Jr., and ORSEMAS T. X. ADAMS, citizens of the United States, residing at Chicago, Illinois, have invented certain new and useful Improvements in Apparatus for Decomposing Metallic Salts and Desulphurizing Ores, of which the following is a specification.

The object of our invention is to provide an apparatus for mechanically decomposing metallic salts and their resulting material, when the substances treated are in a molten condition, by the action of centrifugal force and dividing them into separate and distinct classes; and our invention consists in the features and details of construction hereinafter described and claimed.

In the drawing we have shown a vertical section of our improved apparatus, showing two receiving-vessels arranged in proper relation to each other, together with the supporting-shaft and running-gear, part of which is in elevation.

In making our improved apparatus for decomposing chemical compounds, metallic salts or salts of metals, and desulphurizing ores we provide two or more receiving-vessels V, adapted to receive the substances to be treated when in a molten condition, and arrange them in such relation to each other that, while they are separate and distinct from each other and separably rotatable, the material treated is thrown by the action of centrifugal force from one into another. These receiving-vessels may be made in such a way as will secure the required strength and reduce the conduction of heat from the interior to the exterior. They may be one or both surrounded by a curbing and in other respects made so as to best subserve the end in view and permit of their being independently rotated at a high rate of speed for the separation of particles of different degrees of density or specific gravity in the matter treated, so as to separate the particles differing in specific gravity into their respective classes.

Many of the parts and details of construction, as they do not form the special subject-matter of our present claims, need not be described in detail, as they will be sufficiently

understood from an inspection of the drawing.

As shown in the drawing, the receiving-vessels are arranged in a vertical position and in such relation to each other that the neck or mouth of the lower one extends up through the bottom of the upper one. To permit this, the upper receiving-vessel is provided with a bottom containing a hole or opening of a size to permit the neck or mouth of the lower receiving-vessel to be inserted therein, with, preferably, a slight annular space around it. This space should be sufficient to readily and easily permit the neck or mouth of the lower receiving-vessel to be inserted and removed, and to allow it to revolve freely therein without binding or friction. The lower receiving-vessel is mounted upon a revolute actuating-shaft supported and sustained in proper and suitable bearings.

The upper receiving-vessel is provided with a neck or mouth above the neck or mouth of the lower vessel, and preferably of a diameter slightly larger than the diameter of the hole or opening in its bottom, through which the neck or mouth of the lower receiving-vessel is inserted. It is supported from above by a revolute actuating-shaft mounted and supported in proper and suitable bearings. Its neck or mouth is preferably provided with side holes or openings, as shown in the drawings, to permit the material thrown off by the action of centrifugal force to be discharged therethrough into an annular tub or other receptacle arranged to receive the same. The revolute actuating-shaft sustaining the upper receiving-vessel is preferably made hollow, so that the molten material to be treated may be introduced into the receiving-vessels by flowing down through such hollow actuating-shafts. To prevent the material from coming into contact with the sides of the hollow actuating-shaft, we prefer to insert therein a tube or pipe A, through which the material flows and is kept isolated from the sides of the actuating-shaft itself.

The actuating-shafts of each of the receiving-vessels are provided with pulleys or belt-surfaces and connected by belts with pulleys

or belt-surfaces on power-shafts, or provided with other suitable means to enable them to be rotated and to rotate the receiving-vessels with their loads of molten materials. By proportioning the size of the pulleys or belt-surfaces the two actuating-shafts, with their receiving-vessels, may be revolved at different rates of speed, as may be desired.

As above said, we prefer to make the neck or mouth of the upper receiving-vessel somewhat larger in diameter than the hole or opening in its bottom, through which is inserted the neck or mouth of the lower vessel. This construction will insure the discharge of the material thrown off by the action of centrifugal force and prevent it from escaping from the opening around the neck or mouth of the lower receiving-vessel, and thus insure a constant upward movement of the material being introduced and treated, so that it will pass from the bottom of the lower receiving-vessel to the discharge-openings in the neck or mouth of the upper receiving-vessel.

To permit the upper receiving-vessel to be emptied without disturbing the lower vessel, means may be employed to lift it vertically a sufficient distance to enable its bottom to clear the neck or mouth of the upper receiving-vessel, when it may be removed to one side and its contents opened.

Both of the receiving-vessels may be made separable in the plane of their largest diameter, so that they may be opened and the material remaining therein emptied.

If, now, the two receiving-vessels are arranged as above described and rotated at a high rate of speed, the molten material falling down upon the bottom of the lower one of the receiving-vessels is immediately thrown by the action of centrifugal force against its sides and walls, where the heaviest particles accumulate in an increasing mass, displacing or forcing out the lighter particles. These lighter particles are carried up and discharged by the action of centrifugal force through the neck or mouth of the lower vessel, when they are immediately carried against the sides of the upper vessel. Here the heavier particles of the matter discharged from the lower vessel will be thrown and accumulate against the sides of the upper vessel, and again displace or crowd out the lighter particles, which are again carried up and discharged by the action of centrifugal force through the holes or openings provided in its neck or mouth. We will thus have the heaviest particles accumulated by themselves in the lower one of the receiving-vessels and the lighter particles accumulated by themselves in the upper one of the receiving-vessels, while the lightest particles, composed of slag and worthless residue, will for the most part be thrown off and discharged at the top.

In the drawing we have shown but two receiving-vessels, and have shown them arranged in a vertical position, which is the position which we prefer.

In our present application the distinguishing feature or principle which we particularly desire to secure is the separation of the particles of the material treated into different classes by the employment of two or more receiving-vessels adapted to revolve independently of each other, discharging the molten material successively from one into the other by the action of centrifugal force, and thus subjecting it to more than one treatment while still in a molten condition, until the worthless particles are thrown off and discharged.

What we regard as new, and desire to secure by Letters Patent, is—

1. In an apparatus for decomposing metallic salts or salts of metals and desulphurizing ores when in a molten state, the combination of a compound or multiplex revoluble receiving-vessel adapted to receive molten material to be treated, comprising two or more vessels unconnected and separate from each other, severally rotatable, but in such relation to each other that the material treated is successively carried by the action of centrifugal force from the vessel in which it is first treated to the next adjacent vessel, to deposit and retain the heaviest particles in each vessel in which it is treated, a revoluble actuating-shaft rotating such compound or multiplex vessel as it revolves, and means for rotating the actuating-shaft, substantially as described.

2. In an apparatus for decomposing metallic salts or salts of metals and desulphurizing ores when in a molten state, the combination of a compound or multiplex revoluble receiving-vessel adapted to receive molten material to be treated, comprising two or more vessels unconnected and separate from each other, severally rotatable, but in such relation to each other that the material treated is successively carried by the action of centrifugal force from the vessel in which it is first treated to the next adjacent vessel, to deposit and retain the heaviest particles in each vessel in which it is treated, revoluble actuating-shafts severally sustaining and rotating the vessels, one of the said shafts being hollow for the admission therethrough of the molten material into the vessel to be treated, and means for rotating the actuating-shafts, substantially as described.

PHINEAS H. ADAMS, JR.
ORSEMAS T. X. ADAMS.
